UNITED STATES PATENT OFFICE.

MILO C. NEWTON AND JOSEPH A. GREMLING, OF DELPHOS, OHIO, ASSIGNEES TO THE E. & N. MANUFACTURING COMPANY, OF DELPHOS, OHIO, A CORPORATION OF OHIO.

WRINGER MOP.

Application filed February 11, 1928. Serial No. 253,683.

This invention relates to wringer mops of the type in which the mop cloth is wrung by means of a hand crank carried by the handle of the mop.

5 This invention has among its objects the provision of an improved mop supporting ferrule of simple and inexpensive construction which, in addition to supporting the mop head, provides a support and bearing for the hand crank to which the rear end of the mop cloth is attached.

10 15 A further object is to provide a construction in which a hand crank is mounted in the ferrule beyond the end of the wooden handle so that if the wooden handle is broken, it can be replaced without disturbing any part of the wringer mop.

20 25 A further object of the invention is to provide a connection between the ferrule and the mop cloth supporting head such that the head may be supported in a wringing position such that the pull on the head during the wringing of the cloth is so transmitted to the ferrule that neither the head nor the ferrule is subjected to severe bending stresses.

With the above and other objects in view, the invention may be said to comprise the wringer mop as illustrated in the accompanying drawings hereinafter described and particularly set forth in the appended claims, together with such variations and modifications thereof as will be apparent to one skilled in the art to which the invention appertains.

30 35 Reference should be had to the accompanying drawings forming a part of this specification in which Figure 1 is a plan view of the mop in mopping position.

40 Fig. 2 is a longitudinal section taken on the line indicated at 2-2 in Fig. 1.

45 40 Fig. 3 is a side elevation showing the mop in wringing position with the mop cloth hanging loose, the mop cloth supporting head and its supporting length being shown in section.

50 45 Fig. 4 is a side elevation of the mop showing the mop cloth twisted for wringing.

55 50 Fig. 5 is a section taken on the line indicated at 5-5 in Fig. 4.

Referring to the accompanying drawings, the mop is provided with the usual wooden handle 1 to the end of which is attached a sheet metal ferrule 2. A mop cloth 3 in the form of an endless loop is carried by the ends of the handle, the rear end of the mop cloth being supported in a loop 4 at the lower end

of a hand crank 5 journaled in the ferrule. The forward end of the mop cloth is supported on a cross bar 6 detachably secured to the forward end of a supporting and pressure applying head 7 which is preferably in the form of a substantially rectangular sheet metal plate suspended from the forward end of the ferrule by means of a short link 8. The link 8 is connected to the head 7 intermediate its ends, but nearer the rear end of the head than the forward end thereof. When the mop is in use, the link 8 swings down flat upon the top of the head 7, as shown in Fig. 2, so that pressure may be applied through the handle to the head 7 centrally thereof to maintain a substantially uniform pressure on the mop cloth beneath the head. The ferrule 2 is formed of a single piece of sheet metal and has a rear end portion 9 of tubular form to receive the handle 1. The edges of the sheet metal abut along the under side of the ferrule throughout the length of the tubular portion, but one edge is provided with a projection 10 which fits into a recess of similar form in the other edge of the sheet metal. The hand crank 5 has a vertical bearing portion which extends diametrically through the tubular portion of the ferrule forwardly of the forward end of the handle 1, this vertical portion fitting in openings in the top and bottom of the ferrule, the bottom opening being through the projection 10 so that the bottom opening does not intersect the same and lateral thrusts on the edges of the springs in the operation of the wringer do not distort the ferrule. At its forward end, the ferrule is provided with a channel shaped portion 12 with downwardly extending flanges, the channel shaped portion being of substantially the same width as the tubular portion of the ferrule, but of less depth, the sheet metal being cut away to shorten the flanges of the channel. The link 8 is of channel form provided with side flanges 13 which overlie the side flanges of the channel portion 12 of the ferrule and these flanges are pivotally connected by a transverse pivot pin 14. The sheet metal head 7 has flanges 15 struck up from the body thereof adjacent its rear end and the lower end of the link 8 lies between these flanges and is pivotally connected thereto by means of a transverse pivot pin 16.

Rearwardly of the pivot pin 14, the flanges of the channel portion 12 of the ferrule are provided with transversely alined notches 17, 110

which are adapted to receive the beaded rear edge 18 of the head 7, to hold the head in wringing position as shown in Figs. 3 and 4. The head 7 projects rearwardly from pivot 16 5 a distance sufficient to engage the channel portion of the ferrule and when the bead 18 is seated in the notches 17, the head 7 is held at an angle such that the pull on the mop cloth caused by twisting the same by means of the 10 hand crank 5 is exerted on the head and transmitted largely as end thrust against the underside of the ferrule, the leverage and the direction of thrust being such that excessive bending stresses are not exerted either upon 15 the head 7 or upon the ferrule.

The ferrule, which is made of a single piece of sheet metal, is of very simple construction and, since all of the mop cloth supporting and wringing devices are mounted 20 on the ferrule forwardly of the handle, a broken handle can be replaced without disturbing any part of the wringer mop. In addition, the hand crank and the mop cloth supporting head are so mounted upon the 25 ferrule that effective wringing action is obtained without danger of springing any of the parts out of shape. The present invention thus provides a wringer mop of very rugged and durable construction which is of 30 relatively light weight, which is inexpensive to manufacture and which is easily operated.

What we claim is:

1. In a wringer mop, a handle, a sheet metal ferrule having a tubular rear end portion fitting on the handle and an elongated forward end portion of channel shape with downwardly extending flanges provided with notches adjacent the inner end of the channel portion, a hand crank journaled in the 35 tubular portion of the ferrule and having a cloth holding loop below the ferrule, a short link pivoted at its upper end to the forward end of the ferrule, and a head pivoted intermediate its ends to the lower end of said link, the pivotal connection between the head and link being nearer the rear end than the forward end of the head, said head having means at the forward end thereof for holding 40 a mop cloth and having a rear end portion engageable in the notches of the flanges of the channel portion of the ferrule.

2. In a wringer mop, a handle, a one piece sheet metal ferrule having a tubular rear end portion fitting on the handle and a forward

end portion in the form of a downwardly 55 facing channel, the edges of the flanges of which are above the bottom of the tubular portion, a short link pivoted at its upper end to the forward end of the ferrule, a head pivoted intermediate its ends to the lower end of said link, said head having at its forward end means for holding the forward end of a 60 mop cloth, a hand crank journaled in the tubular portion of the ferrule and having a loop to receive the rear end of a mop cloth, and notches in the flanges of said channel portion adjacent the inner end thereof for holding the head against movement during 65 the wringing operation.

3. In a wringer mop, a handle, a ferrule having a tubular rear end portion fitting on the handle and an elongated channel shaped forward end portion, a hand crank having a cloth holding loop rotatably mounted in the tubular portion of said ferrule beyond the 70 end of the handle, a link pivoted to the forward end of said ferrule, and a head pivoted intermediate its ends to said link, said head having a rear end portion engageable with the edges of the flanges of the channel shaped 75 portion of said ferrule and having cloth holding means at its forward end.

4. In a wringer mop, a handle, a ferrule formed from a single piece of sheet metal and having its rear end portion bent to tubular form to fit on said handle with the edges of the sheet metal abutting along the under side of the ferrule, one edge of the sheet metal intermediate the ends of the tubular portion having a projection and the other edge a recess to receive said projection, said tubular portion having diametrically opposite bearing openings at the upper and under sides thereof, the lower opening being in said projection, a hand crank mounted in said openings and having a cloth holding loop below the ferrule, a link pivoted at its upper end to the forward end of the ferrule and a head pivoted intermediate its ends to the lower end of said link, said head having a rear end portion engageable with the under side of the ferrule forwardly of said hand crank and cloth holding means at its forward end.

In testimony whereof we affix our signatures.
